UNITED STATES PATENT OFFICE.

JOHN MANNING VAN HEUSEN, OF JAMAICA PLAIN, MASSACHUSETTS.

SHIRT.

1,277,786.

Specification of Letters Patent. Patented Sept. 3, 1918.

Application filed December 27, 1917. Serial No. 209,031.

To all whom it may concern:

Be it known that I, JOHN MANNING VAN HEUSEN, a citizen of the United States, residing at No. 101 Robinwood avenue, Jamaica Plain, in the county of Suffolk, State of Massachusetts, have invented certain new and useful Improvements in Shirts, (Case A;) and I do hereby declare the following to be a full, clear, and exact description of the invention, such as will enable others skilled in the art to which it appertains to make and use the same.

This invention relates to improvements in collar bands or neck bands of shirts, which neck bands or collar bands are made of multiple ply interwoven fabric.

According to the present invention, the collar band or neck band is made of a heavy fabric, preferably and advantageously a two or three ply interwoven fabric, which is provided with a divided edge by means of which it is secured to the shirt, or which is provided with a single ply extension, or a portion thinner than the main portion of the neck band, to which the shirt is secured.

The invention will be described more in detail in connection with the embodiments thereof illustrated in the accompanying drawings, in which—

30 Figure 1 illustrates the neck band or collar band as applied to a shirt;

Fig. 2 is an enlarged sectional view of the collar band;

Fig. 3 is a still further enlarged and exaggerated diagrammatic sectional view of the band;

Figs. 4 and 5 are sectional views of modified constructions of bands applied to the shirt;

40 Fig. 6 is an enlarged view of one end of a modified construction of the band;

Fig. 7 is the back view of the back portion of the band showing a modified construction;

45 Fig. 8 is a sectional view of the band of Fig. 7, taken through the back button-hole;

Fig. 9 is a section of fabric from which the band may be made;

Fig. 10 is a longitudinal cross-section of 50 the fabric of Fig. 9;

Fig. 11 is an enlarged view showing one end of the band made from the fabric of Figs. 9 and 10; and

55 Fig. 12 is a sectional view of the band of Fig. 11.

According to the present invention, the

neck band, in its preferred embodiment, is made of a single continuous fabric woven of the proper width for the band, so that it will have selvage edges, and require no 60 added binding at its edges. The fabric is a relatively thick and heavy fabric, so that a single thickness of the fabric will suffice for the band, and will have sufficient body and stiffness, without undue rigidity, to give to 65 the band the proper form and shape when applied to the shirt. This thick and heavy fabric is preferably a multiple ply interwoven fabric, such as a two ply fabric with intermediate filling threads, or a three ply 70 fabric with the plies interwoven to form an integral fabric.

The heavy fabric is provided with an extension which is thinner than the main body of the band. This extension may be a single ply extension, in the case of a multiple 75 ply fabric, or it may be in the form of two separate plies which are not interwoven and which, therefore, form a divided edge between which the shirt can be secured, and 80 the band thereby secured to the shirt.

Thus, in Fig. 2, there is shown a three ply fabric 2, secured to the shirt 1, by the two rows of stitches 10. This fabric is illustrated in an exaggerated and diagrammatic manner in Fig. 3, from which it will be noted that the fabric is made up of three plies 5, 6 and 7, interwoven throughout the main width of the fabric, but with the two outer plies extended beyond the main portion of the fabric in the form of single plies 8 and 9, between which the shirt 1 can be secured in the manner indicated in Fig. 2.

In the modification of Fig. 4 the fabric is shown as a two ply fabric 2^a having a divided edge similar to that of the fabric of Figs. 2 and 3, between which the shirt 1^a is secured by the rows of stitches 10^a.

In Fig. 5 the band is shown as made of three ply interwoven fabric 2^b, having a single ply extension 8^b to which the shirt is secured in any suitable manner. The edge of the fabric of the shirt 1^b may thus be folded over and stitched to the single ply extension 8^b, by two rows of stitches so that the 100 edge of the shirt will be thereby bound and hidden from view.

In the various fabrics illustrated in Figs. 2 to 5 inclusive, the fabric is woven of uniform construction throughout its length, so 110 that the button-holes 3 and 4, may be made therein, and so that the neck band will be

then completed except for the binding of the ends of the band where a raw edge remains. That is, where the fabric is woven of uniform width and with selvage edges, 5 no binding for the edges of the band will be necessary, as would be the case if the fabric were cut from a band of greater width, and the upper edge of the band, for example, were left unfinished. In such a 10 case, an added binding would be required for the unfinished edges of the band.

The ends of the band may be bound or finished in any appropriate manner. Various ways of effecting this end finish or binding are illustrated in Figs. 6 and 12.

In the neck band of Fig. 6, the end of the band is provided with suitable binding 11, which may be in the form of the usual button-hole stitching.

20 The finish or binding of Figs. 11 and 12, is made from a specially woven fabric illustrated in Figs. 9 and 10. This fabric 19 is interwoven throughout the main portion of its length but the interweaving is omitted 25 between the points indicated at 20 to leave a space 21 where the single thicknesses of fabric are not interwoven and are freely separable from each other. By weaving the lengths of the fabric 19 of sufficient length 30 so that the spaces 21 are the proper distance apart, the band can be cut at these spaces and the single thicknesses of fabric folded in and stitched in the manner indicated in Figs. 11 and 12, thereby forming 35 a binding for the edge of the band and giving it a finished appearance.

In case it is not desired to make the button-hole at the back of the neck band extend through the entire thickness of the 40 band, the neck band may be separately woven so that, in the case of a multiple ply fabric, certain plies of the fabric will not be interwoven where the back button-hole is to be located. Such a modified weave of 45 fabric is illustrated in Figs. 7 and 8. The main portion 12 of the fabric is interwoven in the manner above described, but the interweaving is omitted between the points indicated at 14 thereby leaving a portion 15 50 through which the button-hole may be made. As indicated in Fig. 8, the fabric may be a three ply fabric with the two inner plies interwoven and provided with a divided edge between which the shirt is stitched at 55 18. The outer separate ply 15 may have the button-hole 16 therein and it may be united to the inner plies of fabric by stitching or interweaving 17 at the upper edge

of the band. The portion 15 will then be separated at its bottom edge so that the 60 back collar button may be readily inserted.

The collar band may be woven in the form of a straight band of fabric, or the band may be curved so that, when applied to the shirt it will more readily conform and adjust itself to the shape desired in the completed shirt.

It will be evident that the band may be made of different materials, that is, that a more expensive material or more attractive 70 material may be used for the outer exposed ply of the fabric than for the intermediate or the inner layer or ply.

It will be evident also, that various modifications can be made in the weave of the 75 fabric from which the neck band is made, while still retaining the advantages characteristic of the invention.

The provision of the neck band such as that above described involves a simplicity 80 in shirt construction, and avoids a large number of sewing machine operations or the use of a large number of single plies of fabric which are required to be folded and 85 stitched together.

Having thus described my invention, what I claim is:

1. A shirt provided with a collar band of multiple ply interwoven fabric having an extension thereof thinner than the main 90 portion of the band by which the band is secured to the shirt.

2. A shirt provided with a collar band of multiple ply interwoven fabric having one or more plies thereof extended from the 95 main portion of the band and having the shirt secured to the band by said extensions.

3. A shirt provided with a multiple ply interwoven collar band having a divided edge by means of which the collar band is 100 secured to the shirt.

4. A shirt provided with a collar band of multiple ply interwoven fabric provided with one or more single ply extensions by means of which the band is secured to the 105 shirt, said band being woven of the proper width so that the edges of the band require no added binding.

5. A shirt provided with a collar band of multiple ply interwoven fabric having one 110 or more single ply extensions by means of which the band is secured to the shirt, and said collar band having a portion of the interweaving omitted at the back button-hole.

In testimony whereof I affix my signature. 115
JOHN MANNING VAN HEUSEN.
